Application October 20, 1930, Serial No. 489,888

5 Claims. (Cl. 34—48)

This invention relates to paper machinery, and particularly to paper machinery having rotatable paper carrying drying rolls or the like.

One of the principal objects of the invention is the provision in paper machinery, such as paper driers and the like having rotatable drying rolls, of a roll drive comprising a plurality of units having an arrangement of parts providing for flexibility in assembly whereby the units may be joined into series of groups of desired proportions in which the driving loads are satisfactorily distributed.

Another object of the invention is the provision in paper machinery of a drying roll drive incorporating drive units which are adapted to quietly and efficiently transmit the driving loads; the drive units comprising compact enclosed assemblies having simple and effective operating adjustment of the several parts, and in which the parts are suitably supported to provide a substantial structure capable of sustained use without deterioration of the moving parts.

Other objects and advantages of the invention will be apparent from the following description, the accompanying drawings and the appended claims.

In the drawings, which disclose a preferred embodiment of the invention—

Fig. 1 is a diagrammatic showing of paper machinery having a drier roll drive constructed in accordance with this invention;

Fig. 2 is a fragmentary enlarged view of a portion of Fig. 1;

Fig. 3 is a sectional view taken on the plane of the line 3—3 of Fig. 2;

Fig. 4 is a plan view of the drier roll and its attached drive; and

Fig. 5 is a sectional view taken on the plane of the line 5—5 of Fig. 4.

The drawings, in which like characters of reference designate like parts throughout the several views thereof, illustrate a paper drier which comprises a plurality of driven rolls through which a web of paper 10 is adapted to travel during the process of its manufacture. Each roll 13 of the drier is provided with an individual driving unit 14 comprising intermeshing gears of relatively small over-all dimensions, suitably housed, and having provision for joining the drive units by a common shaft 15 whereby the units and associated rolls may be joined into groups for the transmission of power from a common source. The power drive is arranged so that several groups of rolls may be joined into a series, and, if desired, several series may

be arranged to provide a complete assembly having a common drive. The arrangement of the drive is such that any desired number of roll units may be combined into a group, and any number of groups may be joined into a series; the number of series used being dependent only on the total roll requirements of the drier so that a drier assembly of any desired size may be provided.

Preferably the drive units 14 are each provided with a short section of driving shaft which is adapted to be readily joined to the shaft of the driving unit of an adjacently positioned roll. As shown in Fig. 1, several adjacently positioned rolls 13, each having an independent driving means 14, are joined by assembly of the driving shafts 15 to provide a roll group 16 shown as comprising five rolls. Positioned above the group 16, and spaced therefrom to provide a suitable staggering of the rolls, is a second group 17 having drive shafts 15 joined similarly to the group 16. The roll groups 16 and 17 form a roll series, designated by the letter A, for which a common drive 18 is provided. As shown, each group assembly of the drive shafts 15 is provided with a sprocket 20. A counter-shaft 21 is provided in the drier drive for transmission of power to the series and has a sprocket 22 carrying a drive chain 23 which engages the sprockets 20 and is maintained in proper driving engagement therewith through the provision of a suitable adjustable idler sprocket 24. An enclosing housing 26 is provided for the chain drive which, in addition to serving as a safety guard, serves also to properly lubricate the chain and maintain it in a quiet and efficient operating condition. Positioned adjacent the roll series A is a similarly arranged series B comprising a roll group 16' and a group 17' having a common drive 18' similar to that of series A. As illustrating an example of power drive for the grouped rolls, sprocket 22 for the drive 18 of the series A and the sprocket 22' for the drive 18' of the series B are shown positioned on a common counter-shaft 21 upon which is provided a cone pulley 24 which stands aligned with an oppositely positioned cone pulley 25 mounted upon a main driving shaft 26; a belt 28 being provided to transmit power from the main shaft 26 through the pulley 25 and pulley 24 to the counter-shaft 21. Any suitable source of power, such as the motor 27, is provided for the main shaft 26. Additional rolls, designated as series C and D, are shown having a grouped drive similar to that described for the series A and B. The series

C and D are driven from a common counter-shaft 21' arranged with respect to the common source 26 similarly to the counter-shaft 21. If desired, individual drive motors may be provided 5 for each counter-shaft of the assembly or, if further division is desirable, individual motors may be provided for each roll series. Additional roll series beyond the four illustrated, may be added to provide the required total number of 10 rolls for the drier.

The arrangement of the roll drive is such that the driving loads are uniformly distributed. This not only provides a condition whereby the power transmitting parts may be of minimum size, but 15 also it results in an arrangement providing synchronous driving of the grouped rolls. Each roll 13 of a group is provided with a power transmission which is independent of each other roll of the group and all of the rolls of the group are 20 driven in synchronism through the assembled driving shafts 15 which provide a common driving shaft for the grouped rolls. The rolls of adjacent groups are synchronized through the provision of a common drive 18 so that all of the 25 rolls of a series will rotate at a uniform speed for proper support of the paper web carried thereon. Means are provided whereby the speeds of the several series may be independently varied, either by the provision of independent motor drives or 30 by an arrangement of cone pulleys, as shown, in which a belt shifting mechanism of well known construction is incorporated in the drive from the common power source. Varying conditions of 35 expansion or contraction in the paper web encountered during the drying process may necessitate operating one series at a slightly different speed than an adjacent series. It is to be understood that the grouping of rolls may be varied as desired and that a greater or lesser number than 40 the five rolls shown may constitute a roll group, also the arrangement of the rolls in a series may be altered to suit various conditions.

By arranging the roll drive into units each 45 individual gear transmission of intermeshing gears is required to carry the load of only one roll and consequently the parts need only be provided of a size sufficient to carry this single roll load. The intermeshing gears of a roll unit are of such 50 character that a considerable speed reduction is provided between the driving pinion and the driven gears; consequently the group driving shaft 15 which rotates relatively at quite high speed, may be provided of small size and still sustain the driving load of the group without over-load, and without torsional stresses sufficient to 55 cause torsional movement in the shaft. By driving each roll independently from the shaft 15 through parallel arranged duplicate drives there is no opportunity for an accumulated lag such as 60 would occur if the rolls were driven through a connection in which the driving load of one roll is transmitted to the next and that in turn transfers the load of both to the next adjacent roll and so on to the last roll which is required to 65 carry the load of all. In addition to this unequal distribution of driving load in such an arrangement further difficulty is encountered due to the accumulation of lag in the running clearance of adjacent interfitting parts which 70 prevents the synchronous operation of the individual rolls, so readily provided by the parallel drive of the invention. Not only is each unit of a group provided with an independent power transmission but, by driving the groups independently from a 75 common drive 18, each group of a series is also

arranged so that the driving loads are uniformly distributed. When power transmission is provided from a common source, such as the driving shaft 26 for the entire assembly in which the loads are branched to the roll groups and terminate in individual roll drives, the uniform distribution of driving loads throughout the entire system permits parts of minimum size to be used with a consequent saving in the cost of manufacture. Also, such an arrangement of parts permits the rolls to be driven in exact synchronism thereby avoiding the difficulties encountered as a result of lack of synchronism in the rolls which may cause serious injury to the paper web passing over the rolls, and may cause it to tear with 10 consequent waste of time and material.

The flexibility of the roll drive whereby various groupings of rolls may be assembled to meet different conditions of installation is made possible by a construction wherein each roll drive unit 14 20 is of a standardized form which may be readily attached to adjacent similar units and may be grouped to provide an assembly of any desired proportion. As shown, each roll 13 comprises a cylindrical face portion 35 having end walls 36 in 25 which are provided journal shaft extensions 37 and 38. The journal shaft extensions may be formed as an integral part of the roll structure or, as shown, may be separate members suitably held within the roll ends 36. Suitable bearings 30 are provided for the support of the rolls 13 and these are positioned within housings 40 and 41 carried by the machine frame 39. The journal shaft 37 projecting from one end of the roll is made hollow and is provided of sufficient length 35 to accommodate the drive means for the roll. The bearing housing 40 for that journal shaft is of such construction as to provide for the attachment of the drive means and the support of the drive means housing. The bearing housing 41 at 40 the opposite end of the roll is provided with a suitable closure member 42 to properly house the bearing contained therein.

The drive means for a roll comprises a gear 44 suitably fixed adjacent the end of the journal 45 shaft 37, and a driving gear or pinion 45 held in meshing engagement therewith and positioned upon the driving shaft 15. The gear 44 is preferably a hypoid gear, as shown, in which the intermeshing engagement with the driving pinion 50 45 is such as to permit the driving shaft 15 to be positioned spaced from or out of alignment with the axis of rotation of the gear 44. By positioning the driving shaft 15 out of alignment as mentioned, the roll power transmission may be arranged so that the end of the journal shaft is exposed and is readily accessible as for the attachment of a steam inlet.

An enclosing housing 48 is provided for the gears of each roll drive unit and is formed in 60 two halves split horizontally along the line of the shaft 15. It is of symmetrical form so that the drive pinion 45 may be positioned at either of opposite sides of the housing for rotation of the roll in either of opposite directions by merely 65 substituting right-hand cut for left-hand cut gears, or vice versa. The gear housing 48 is provided with extending portions 49 on the line of the shaft 15 for the support of suitable shaft carrying bearings 50, and is provided with an 70 annular flange 52 whereby the gear housing 48 may be joined to the bearing housing 40 for support thereby; suitable attaching screws 53 being provided. As mentioned, the drive units 75 14 are of similar form and each is provided with

a driving shaft 15. The shafts 15 of adjacent drive units 14 may be joined to provide, in effect, a continuous shaft for the rolls of a roll group. Suitable connections, such as the couplings 55 5 shown, may be provided between the shaft sections to provide for the proper driving alignment of adjacent drive units.

The use of hypoid gears for a roll drive permits a compact unit assembly which may be readily 10 housed and, due to the relationship of drive shaft axis to roll axis, one which may be easily connected to adjacent units. Economy results from such usage, not only through the substitution of the small compact hypoid gears for the 15 large diameter spur gears of conventional practice, but also due to the fact that it becomes practically possible to house the gears so that they may operate efficiently by being properly lubricated, and by being protected from deterioration 20 caused by collection of dirt which is inevitable upon exposed parts of a machine. The compact enclosed arrangement of drive parts permits ready access to the drier and eliminates the constant danger to injury from exposed moving parts.

For efficient and economical use of power in the operation of the drier rolls, roller bearings 57 are provided for the roll support and these are mounted within the housings provided in a 30 manner which permits ready adjustment of the bearings. In Fig. 5 the bearing 57 is shown as being of the double row roller type having a common inner race 59 and spaced outer races 60 and 61. The inner race 59 of the bearing is 35 held in fixed relation to the shaft upon which it is mounted as by being provided with a tapered bore which is received upon a similarly tapered portion 62 of the journal shaft 37. Locking nuts 63 threadedly engage the shaft 37 adjacent the small end of the tapered portion 62 and are adapted to be tensioned against the end of the bearing race 59 so that it will be maintained on the taper securely in position with respect to the shaft. As shown, a collar 40 45 64 is mounted on the journal shaft between the inner race 59 of the bearing and the locking nuts 63. The collar 64 is adapted to cooperate with other bearing parts to provide a closure for the bearing housing. A second collar 64' is 50 positioned on the shaft adjacent the opposite side of the bearing race 59 and, like the collar 64, also serves as a housing closure.

Suitable retaining means are provided within the housing for the bearing outer races, and 55 adjusting means are provided for maintaining the bearing outer races in proper operating relationship with respect to the inner race 59 which is held securely in position upon the journal shaft. The retaining means comprises a 60 cylindrical sleeve 65 within which the bearing races 60 and 61 are received; the outer surface of which is slidably received within the bearing housing 40. One end of the sleeve 65 is provided with an internal flange 65' against which the race 61 is adapted to bear, while the opposite end of the sleeve is internally threaded at 66 to adjustably receive a threaded retaining ring 67 having an end portion 67' which is adapted to contact with race 60. The sleeve 65 is 65 adjusted with respect to the housing 40 by means of a series of spaced screws which are carried by an inturned annular flange 40' at an end of the housing 40, and which are adapted to engage the sleeve. The adjusting screws stand parallel with the bearing axis and comprise cap

screws 68 and set screws 69 which are preferably alternately spaced at uniform intervals upon the flange 40'. The cap screws 68 threadedly engage the sleeve 65 and limit movement of the sleeve to the right (as viewed in Fig. 5) by contact of the screw heads with the flange 40'. The set screws 69 threadedly engage the flange 40' and bear against the end of the sleeve 65 to limit its movement to the left. By adjustment of the two groups of screws the retaining sleeve 10 may be moved to provide for proper positioning of the bearing race 61, and may be securely held in place relatively to the bearing housing 40. The retaining ring 67, upon being moved to adjusted position within the sleeve 65, may be 15 locked in place by provision of a plate 70 removably held to the ring by means of a screw 70' and positioned thereon by means of a pin which extends from the face of the ring. The plate 70 is adapted to engage one of a series of 20 serrations 71 which are provided on the inner face of the sleeve 65. This arrangement of parts provides a simple and effective adjusting means for the bearing whereby both outer races may be moved in unison or, if desired, one race may 25 be adjusted independently of the other. Should it become necessary to tighten or adjust the inner race of the bearing with respect to the shaft 37 this may be readily accomplished without disturbing the relative setting of the outer races by 30 loosening the adjusting screws 68 and 69 prior to adjustment of the inner race and by retightening these after the inner race is locked in place. Any slight error in the formation of the tapered portion 62 of a shaft which would cause a variation in the point at which different bearings might be drawn tight, or any tendency of the bearing inner race to expand in service which would necessitate readjustment of this part on the shaft 37 is readily accommodated by the 35 provision of the adjustable retaining means which may be so adjusted that each outer race may be brought up to a proper operating fit without regard to the positioning of the bearing within the housing. Thus the position of the roll 40 45 may be properly maintained at all times with respect to the position of the bearing housing, and need not be altered during bearing adjustments.

Housing closures are provided which cooperate with the collars 64 and 64' to restrain the 50 passage of lubricant from the bearing housing. As shown, one end of the housing is enclosed by a ring 72 which is attached to the housing end by means of screws, and which terminates in an annular flange 72' positioned concentrically with 55 and closely adjacent the collar 64'. Suitable sealing means are provided between the flange 72' and collar 64' such as the interfitting tongue and groove 73, and the sealing rings 74. The opposite end of the housing is enclosed by provision of a flange extension 75 on the retaining ring 64 which terminates in a portion positioned concentrically with respect to the collar 64, similar to the relationship between the flange 72' and shaft collar 64'. Sealing rings 74' are provided 60 between the collar 64 and flange 75.

The bearing housings are shown as being attached to the machine frame 39 in a manner which permits the housings to align themselves with respect to the roll shafts. The face 76 of 70 the machine frame 39 upon which the bearing housings are mounted is grooved to receive a dowel 77 which is preferably a bar of substantially round section. The dowel groove is so formed that the dowel axis will lie in a substantially hori- 75

5 zontal plane perpendicular to the roll axis and the dowel will be positioned half within the machine frame and extending therefrom so that the exposed half may be received within the bearing housing.

10 The face of the bearing housing which lies adjacent the machine frame face 76 is tapered as at 78 from a center line extending perpendicularly to the roll axis; this center line being parallel 15 to a groove formed in the bearing housing face for reception of the exposed portion of the dowel. The parts are so proportioned that a clearance space is provided between the adjacent frame and bearing housing faces. This initial clearance space together with the tapered faces 78 20 of the housing, which provide in effect a convex face, permits a rocking movement for the bearing housing. The holding bolts 79, by which the bearing housings are attached to the frame 39, 25 are aligned with the dowel axis so that the attached housing may readily move independently of the frame on an axis perpendicular to the journal shaft 37. Such an arrangement permits the bearing housing to be aligned with the shaft 37 so that the roll supporting bearing 57 will be 30 free of any strains due to misalignment of parts or to warping of the machine frame. By supporting the gear housing 48 from the bearing housing 40 as shown, the entire drive structure 35 is maintained in proper operating alignment. Should a single group driving shaft 15 be provided instead of the assembled short sections, the possibility of misalignment in this part is obviated by provision of the freedom of movement in the bearing housings and attached gear housings.

40 Means are provided for introducing a fluid flow, such as steam, to the interior of the hollow rolls. As shown, a tubular member 80 threaded- 45 ly engages a plate 81 which is suitably attached to the end of the hollow roll journal shaft 37, as by the screws 82, so that the tube 80 is positioned in axial alignment with respect to the shaft 37. The plate 81 also serves to hold the gear 44 upon the shaft 37; driving engagement being provided 50 with a key not shown. The tubular member 80, which may be a piece of common pipe, is of sufficient length to project from the point of attachment to the plate 81 through an opening 84 provided in the gear housing 48 and to extend therefrom a distance sufficient to permit the attachment 55 of a fitting 86 having a threaded connection 87 to a pipe 88 connected to a source of steam supply. The fitting 86 is supported from the stationary gear housing 48 through the provision of attaching studs 87 which project from the housing and extend through ears on the fitting. The interengagement of studs and fitting ears serves to maintain the fitting stationary and in alignment with the rotating tube 80.

60 The steam fitting 86 and pipe 80 are maintained in fluid tight relationship by tensioning the fitting against a suitable packing carried by the pipe. To position the packing 89, the tube 80 is provided on the exterior of the gear housing 48 with a ring 90 suitably fixed thereon as by welding. The packing 89, which is preferably a metallic or carbon ring, is carried on the end portion of the tube 80 against the ring 90 and is provided with a face 92 of suitable form 70 for contact with the engaging end 93 of the fitting 86. The fitting 86 is held in fluid tight engagement with the pipe 80 through the medium of the packing 89 by provision of springs 94 which are positioned on the studs 87 and are tensioned 75 between nuts 95' on the ends of the studs 87 and

the ears 97' of the fitting 86. The holes in the fitting ears 97' through which the studs pass are counter-sunk. The small diameter bore of the holes provides a close fitting engagement with the studs to maintain the alignment of the fitting, while the countersunk portions serve as enclosing housings for the springs. By supporting the fitting 86 in a secure manner from the gear housing 48, and in turn carrying the gear housing from the bearing housing 40, a substantial support is provided for the steam fitting 86 which is sufficiently rigid to withstand the strains set up in the connecting steam pipes due to expansion therein upon temperature change. By directing these strains into a substantial supporting structure the packed steam joint is relieved of all wear except that resulting from friction of the moving parts. Being well adapted to sustain this the packing will provide satisfactory operation over long periods of time.

An outlet is provided for the roll interior in the form of a siphon pipe 95 which serves, for example, as a discharge for the condensate which collects therein. The siphon pipe 95 passes through the steam fitting 86, the hollow journal shaft 37, to the interior of the roll where an elbow 96 is provided to which is attached a downwardly extending pipe portion 97 which terminates a short distance from the bottom of the roll interior. A suitable packing gland 99 is provided in the steam fitting 86 at the point of entrance of the siphon pipe 95 and a supporting collar 101 is provided on the interior of the steam fitting for further support of the siphon pipe; the collar 101 being provided with spaced holes 102 for the passage of steam therethrough. A bracket member 104 is provided on the interior end of the journal shaft through which the siphon pipe passes. As shown, the bracket 104 comprises a ring-like structure having an outwardly extending flange 105 which is attached to the inner end of the journal shaft as by the screws 106. The bracket is provided with an axially positioned sleeve 108 having a cylindrical bearing member 109 for support of the inner end of the siphon pipe. The bearing portion 109 is preferably formed of some composition which provides its own lubricant and is formed of such size as to support the siphon pipe without appreciable shake or rattle. By so supporting the inner end of the siphon pipe the open end of the downwardly extending portion 97 is maintained in substantially fixed relation to the inner surface of the roll, and also the siphon pipe is prevented from coming into contact with the journal shaft so that rubbing and consequent wear on the siphon pipe at this point is eliminated. The bracket 104 serves not only as a supporting means for the siphon pipe but provides also a deflecting means whereby the steam passing into the roll interior is uniformly distributed therein so that an even temperature may be maintained throughout the roll. The bracket 104 is webbed, as indicated at 111 adjacent the point of attachment of the sleeve 108, and is provided with several holes 112 which stand perpendicularly to the roll axis; three or four half inch holes being a suitable number. The bracket serves as a baffle and prevents the steam from entering the roll interior as a jet which would maintain its formation until the opposite end of the roll is reached and would therefore cause unequal heating of the roll interior. Through the provision of obstructions in the form of the sleeve 108 and supporting webs 111 suf- 75

ficient resistance is set up to the passage of steam to cause a portion of the steam flow to pass laterally of the roll through the openings 112 so that the steam is uniformly distributed to the roll interior and an equal heat transfer to the wall of the roll results.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

15 1. In paper machinery of the character described, a hollow rotatable roll, a hollow journal shaft therefor, means for supplying steam through said hollow journal shaft, a stationary siphon pipe extending within said journal shaft 20 and continuing to the interior of the roll, and supporting means for said siphon pipe, said supporting means comprising a bracket member attached to the roll and positioned adjacent the inner end of said journal shaft and providing a bearing for said siphon pipe, said bracket member having a passage extending axially of the roll in alignment with and of substantially the same outside diameter as the hole in the journal shaft and having additional restricted passages 25 extending substantially transversely of the roll axis for distributing steam supplied through the hollow journal shaft along the entire length of the roll.

2. In paper machinery of the character described, a machine frame, a hollow rotatable roll having a hollow journal shaft providing communication to the interior thereof, supporting means for said roll comprising a bearing housing mounted on said machine frame, means for 30 introducing a fluid flow to said journal shaft for passage to the interior of the roll, said last mentioned means comprising a non-rotatable fluid

conduit mounted in fluid tight contact with an end portion of said journal shaft, and a stationary supporting connection from the bearing housing for the fluid conduit.

3. In paper machinery of the character described, a hollow rotatable roll having a hollow journal shaft, driving means for said roll, said driving means comprising a gear attached to said journal shaft, a driving shaft, a driving pinion mounted thereon in meshing engagement with 10 said gear, an enclosing housing for said driving means, a fluid conduit, and a bolt connection between the fluid conduit and the drive enclosing housing to hold the fluid conduit in fluid tight connection with the journal to provide a fluid 15 passage from the conduit to the roll interior.

4. In paper machinery of the character described, a machine frame, a hollow rotatable drier roll having a hollow journal shaft providing communication to the interior thereof, bearing means 20 for said journal shaft mounted on said machine frame, a hypoid gear fixed to said journal shaft adjacent said bearing means, a driving shaft extending across but spaced from the journal shaft 25 axis, a drive hypoid pinion mounted on said shaft and driving said hypoid gear, and means rotatably supporting said driving shaft.

5. In paper machinery of the character described, a machine frame, a hollow rotatable drier 30 roll having a hollow journal shaft providing communication to the interior thereof, supporting means for said journal shaft comprising a housing mounted on said machine frame and an anti-friction bearing supported in said housing, a hypoid gear fixed to said journal shaft closely 35 adjacent said bearing, a driving shaft extending across but spaced from said journal shaft axis, a drive hypoid pinion mounted on said shaft and driving said hypoid gear, and means rigid with said housing rotatably supporting said driving 40 shaft.

HERMAN L. KUTTER.
